UNITED STATES PATENT OFFICE

2,479,831

HAND LUGGAGE

William L. Goodman, Jr., Highland Park, Ill., assignor to Platt Luggage, Inc., Chicago, Ill., a corporation of Illinois

Application December 15, 1947, Serial No. 791,699

3 Claims. (Cl. 312—172)

1

The present invention relates to luggage and particularly to the provision of luggage with new and improved garment hanger supporting structure and has for its primary object the provision of supporting structure enabling a greater number of garments, especially women's padded shoulder type garments, to be packed in hand luggage.

Travelers are apt to want to pack too many garments in luggage not designed to carry as much as the travelers desire. As a result the garments are apt to become wrinkled. To avoid wrinkling, others travel with less clothing than they would like to take along.

The difficulties attendant traveling with sufficient clothing and without excess luggage are increased in the case of women, who, oftentimes, have to pack dresses and other garments having padded shoulders.

These difficulties are minimized considerably by the present invention which provides luggage with what may be termed twin hanger posts extending in parallel spaced relation from a side wall of the luggage. Dresses and the like are hung on the garment hangers and the hangers are alternately placed on the two posts, thereby to displace and effectively disalign and distribute the added bulk created by the padded shoulders.

It is a further object of the present invention to provide a new and improved hand luggage with garment hanger supporting structure comprising a pair of generally parallel supporting posts. This construction not only enables more garments to be packed with no increased likelihood of wrinkling, but the two posts can be made shorter than one post intended to accommodate a like number of garments and they will not have to extend outside the luggage section in which they are mounted.

Other objects and advantages of the present invention will become apparent during the ensuing description of an embodiment thereof, in the course of which reference is had to the accompanying drawings, in which:

Fig. 1 is a fragmentary elevational view of the inside of hand luggage including the hanger supporting structure of the present invention;

Fig. 2 is a sectional view of the luggage, taken along the line 2—2 of Fig. 1; and

Fig. 3 is a reduced perspective view of the luggage showing the placement of garments on the hangers and of the hangers in the luggage.

Hand luggage constructed in accordance with the present invention enables an increased

amount of padded shoulder type garments to be packed. The invention is particularly adapted to women's hand luggage because of the number of women's dresses which are made with padded shoulders.

A piece of women's hand luggage embodying the present invention and with dresses packed in it is shown in Fig. 3. The luggage is indicated as a whole by reference character 10 and it includes a pair of hingedly connected sections 12 and 14, of which the former includes a side wall 16 and a top wall 18. Dresses 20 are hung upon hangers 22 supported in the luggage in horizontally displaced relation so that the bulk created by the padded shoulders 24 of the dresses may be effectively disaligned and distributed. While but two dresses are shown, it is obvious that an increased number of garments can be packed in the luggage without increased tendency toward wrinkling by reason of the displacement.

The hanger supporting structure comprises what may be termed a "twin hanger post" construction. It includes the posts 26 and 28 which are displaced laterally and extend inwardly from the side wall 16 of section 12. The posts are generally parallel and extend perpendicularly from the inner surface of the side wall. They also have a length approximately equal to the depth of the section. The posts are secured to a supporting plate 30 secured to the downwardly extending end 32 of a generally T-shaped mounting plate 34, the transverse portion 36 of which is secured in suitable manner to the underside of the top wall 18. Mounting plate 34 has a shape conforming to the shape of the interior of the luggage section and the post supporting plate 30 is located immediately adjacent the wall 16.

In order to hold the garment hangers 22 in position, the posts are made polygonal, preferably square, in section and the hangers are provided with upwardly extending hanger plates 38 having square openings. The hangers are also prevented from sliding off the posts accidentally by spring pressed ball detents 40 disposed near the free ends of the posts.

The spacing of the posts 26 and 28 is such that one end of every alternate hanger is near one end wall of the section. Use is thus made of the entire interior of the luggage section.

It is believed that the advantages of the present invention are made evident by the preceding detailed description. In use, the garments, such as women's dresses, are hung on the hangers 22. The hangers with the dresses draped over them

are then placed upon the posts 26 and 28, the hangers being hung alternately on the right and left posts to distribute the bulk created by the padded shoulders 24, as illustrated in Fig. 3. While but two hangers with dresses upon them have been shown placed in the luggage illustrated in Fig. 3, additional hangers with dresses upon them can readily be placed upon the posts. For instance, the third and fifth dresses could be placed upon the post 28 and the fourth and sixth dresses could be placed upon the post 26.

In the illustrated construction, the posts are of a length readily to accommodate three dresses apiece, so that six dresses can readily be packed in the one section of luggage. This can be done, too, without the posts extending beyond the bottom or top walls of the luggage section.

Garments placed in the luggage are adapted additionally to be held in place and folded around a dress bar 42, illustrated in Fig. 2, where it may be seen lying above a curtain 44. Inasmuch as these are conventional elements of women's luggage, they have not been illustrated or described in detail.

While but a single embodiment of the invention has been described in detail, it should be understood that the details thereof are not intended to be limitative of the invention, except as set forth in the accompanying claims.

Having thus described my invention, what I claim as new and desire to secure by Letters Patent is:

1. Hand luggage especially adapted for carrying padded shoulder type garments hung on garment hangers including a luggage section having opposed top and bottom walls, side and end walls, and a pair of longitudinally extending hanger supporting structures fixedly supported in said section upon and near one of said opposed walls, said structures being generally perpendicular to the side wall, of a length and construction each slidably to receive a plurality of garment hangers in longitudinal spaced relation, and offset laterally a short distance substantially less than half the total width of a hanger so that when the garment hangers are placed thereon the ends of hangers on the structures will be displaced relative to each other, with one end of a hanger on one supporting structure nearer the adjacent end than to the center of a hanger on the other supporting structure, thereby effectively to distribute the bulk of the padded shoulders.

2. Hand luggage especially adapted for carrying padded shoulder type garments hung on garment hangers including a luggage section having top, side and end walls, and a pair of longitudinally extending hanger supporting structures comprising part of a structural unit mounted in said section near the top wall, said structures being generally perpendicular to the side wall, of a length approximating the depth of the section and construction each slidably to receive a plurality of garment hangers in longitudinal spaced relation, and offset laterally a short distance such that when the garment hangers are placed thereon the ends of hangers on the structures will be displaced relative to each other so that one end of each hanger on one supporting structure is approximately in the mid region of the adjacent half of each hanger on the other supporting structure, thereby effectively to distribute the bulk of the padded shoulders.

3. Hand luggage especially adapted for carrying padded shoulder type garments hung on garment hangers including a luggage section having top, side and end walls, and a pair of longitudinally extending hanger supporting structures mounted in said section near the top wall, said structures being generally perpendicular to the side wall, of a length and construction each slidably to receive a plurality of garment hangers in longitudinal spaced relation, and offset laterally a small fraction of the width of a hanger corresponding approximately to the width of shoulder padding so that when the garment hangers are placed thereon the ends of hangers on the structures will be displaced relative to each other and effectively distribute the bulk of the padded shoulders.
